UNITED STATES PATENT OFFICE.

JAMES J. WATERS, JR., OF ALTA VISTA, KANSAS.

FOLDING CAR STEP.

Application filed May 11, 1926. Serial No. 108,259.

My invention relates to folding car steps. An important object of the invention is to provide a device of the above mentioned character adapted for use with the steps 5 of railway cars or coaches and which is extremely simple in construction, cheap to manufacture, and convenient to manipulate in use.

An important object of the invention is 10 to provide a device of the above mentioned character, having a step element which may be folded flat upon the lowermost step of the car, or projected to an open position, below the lowermost step, to constitute an 15 extension step.

A further object of the invention is to provide apparatus of the above mentioned character, having their parts so co-related 20 that there is no liability of displacement of the same, when folded, due to the vibration of the train.

Other objects and advantages of the invention will be apparent during the course 25 of the following description.

In the accompanying drawings, forming a part of this specification, and in which like numerals are employed to designate like parts throughout the same:—

Figure 1 is a perspective view of a folding 30 step embodying my invention, showing the same open and in use,

Figure 2 is a similar view, showing parts closed or collapsed,

Figure 3 is a transverse section taken on 35 line 3—3 of Figure 1,

Figure 4 is a fragmentary front elevation of the device, parts collapsed.

In the drawings, wherein for the purpose 40 of illustration, is shown a preferred embodiment of my invention, the numeral 5 designates a car step as a whole embodying sides 6 and steps 7.

The numeral 8 designates L-shaped 45 brackets, embodying horizontal and vertical arms 9 and 10. The arms 9 are rigidly attached to the sides 6 by means of bolts 11, or the like. The vertical arms 10 depend from the horizontal arms 9 and are provided with inwardly projecting stops 12, rigidly 50 attached thereto.

The numeral 13 designates links, arranged 55 inwardly of the brackets 8 and pivotally connected at their upper ends with these L-shaped brackets adjacent to other apexes, as shown at 14. When these links are swung downwardly to a vertical position they en-

gage the stops 12 and their forward swinging movement is limited. The links 13 are adapted to be swung upwardly in a forwardly direction, from the position shown 60 in Figure 1, so that they will assume a horizontal position upon the top of the lowermost step 7, as indicated in Figure 2. A resilient latch 15 is attached to one horizontal arm 9, and is adapted to engage over the 65 adjacent link 13, for holding the same in place.

The numeral 16 designates a step element, which may be formed of metal or any other suitable material. The upper face of this 70 step element is preferably suitably roughened, as by being scored or milled. If desired, this face of the step element may be covered by corrugated rubber, or the like. The step element 16 is rigidly attached to 75 straps 17, extending transversely at the end thereof, and these straps are provided at their forward ends with rounded knuckles 18, see particularly Figure 3. The links 13 are provided at their outer ends with inwardly and laterally bent horizontal stop 80 extensions 19, positioned beneath the knuckles 18 and the straps 17. When the step element 16 is swung to an angle of ninety degrees with relation to the link 13, 85 Figure 3, a portion of the straps will rest upon the stop extensions 19 and hence the step element will be rigidly supported.

Secured to the upper face of the step element 16 and preferably cast integral 90 therewith, is a combined toe-guard and hand-grip 20, positioned adjacent to the inner edge of the step element, as shown.

The operation of the device is as follows:

When the step element 16 is not extended, 95 it lies flat on the top of the lowermost stationary step 7, Figure 2, and the element 20 serves as a toe-guard, limiting the forward slipping movement of the foot. The element 20 is made sufficiently low so that the toe will not be caught under it. The step element 16 is now parallel with the links 13. To extend the step element, the porter or other operator, takes a hold of the element 20 and swings the step element and 100 its links 13 rearwardly and downwardly for two hundred and seventy degrees, until the links 13 become perpendicular and engage the stops 12. The step element 16 is now 105 swung rearwardly and downwardly from the vertical position to the horizontal position, Figure 1, and the stop elements 19 110

support it in this horizontal position. The element 20 is still arranged on the upper surface of the step element and now serves as a toe-guard. The reverse of this operation occurs when the step element is again folded.

It is to be understood that the form of my invention, herewith shown and described, is to be taken as a preferred example of the same, and that various changes in the shape, size and arrangement of parts may be resorted to without departing from the spirit of my invention or the scope of the subjoined claims.

Having thus described my invention, I claim:

1. A pair of substantially L-shaped brackets embodying horizontal and vertical arms, the horizontal arms being adapted to be secured to the sides of a car step adjacent to the lowermost set, laterally extending stops secured to the vertical arms near their lower ends, links pivoted to the L-shaped brackets adjacent to their apexes and adapted to engage with said stops, said links being provided adjacent to their free ends with inwardly extending stop elements, and a step element having knuckles pivoted with the links at points adjacent to and inwardly of said stop elements, the arrangement being such that the step element is adapted to be folded flat upon the lowermost step and to be extended beneath the lowermost step and supported substantially horizontally.

2. A pair of substantially L-shaped brackets embodying horizontal arms and substantially vertical arms depending therefrom, the horizontal arms being adapted to be secured to the sides of a car step adjacent to the lowermost step, the vertical arms being provided near their lower ends with lateral stop elements, links pivotally connected with the brackets adjacent to the tops of the vertical arms and being adapted

to engage said lateral stop elements when swung downwardly to assume positions substantially parallel with the vertical arms, inwardly projecting stop elements carried by the free ends of said links, a step element, straps secured to the step element and having knuckles pivoted to the links inwardly of and adjacent to the inwardly projecting stop elements whereby the step element is supported when swung rearwardly to a position at substantially a right angle to said links, and a combined toe-guard and hand-grip extending longitudinally of the step element adjacent to its inner edge and attached thereto, the arrangement being such that the step element may be folded flat upon the lowermost step and projected beneath the lowermost step and supported in the open horizontal position, the same side of the step element being arranged uppermost when the step element is supported in the raised or lowered position whereby the combined toe-guard and hand-grip projects upwardly above the step element and may function.

3. A pair of supports adapted to be secured to a car step adjacent to the lowermost step, links pivotally connected with the support so that they may be folded flat upon the upper surface of the lowermost step and swung outwardly from this position to depend below the lowermost step in substantially perpendicular positions, means to limit the swinging movement of the links when shifted to the lower perpendicular positions, and a step element pivotally connected with the outer ends of the links in such a manner that the step element may assume a position substantially parallel with said links and also a position at substantially a right angle to said links.

In testimony whereof I affix my signature.

JAMES J. WATERS, JR.
